(57) **CLAIM**

The ornamental design for a stylus, as shown and described.

DESCRIPTION

FIG. 1 is a front perspective view of a stylus;

FIG. 2 is a front view of the stylus of FIG. 1;

FIG. 3 is a rear view of the stylus of FIG. 1;

FIG. 4 is a left-side view of the stylus of FIG. 1;

FIG. 5 is a right-side view of the stylus of FIG. 1;

FIG. 6 is a top plan view of the stylus of FIG. 1;

FIG. 7 is a bottom plan view of the stylus of FIG. 1;

FIG. 8 is an exploded bottom perspective view of the stylus of FIG. 1; and,

FIG. 9 is a front perspective view of the bottom portion of the stylus of FIG. 1 shown separately for ease of illustration.

Features shown in broken lines in FIGS. 1, 4, 5, 6, and 8 form no part of the claimed design.

1 Claim, 6 Drawing Sheets

FIG. 1

FIG. 2

FIG. 3

FIG. 4

FIG. 5

FIG. 6

FIG. 7

FIG. 8

FIG. 9
